OF BELFIELD, NORTH DAKOTA

GAUGE RUNNER

Application filed February 21, 1929. Serial No. 341,616.

This invention relates to a new and useful device in the nature of a plough governor especially adapted to procure an even depth of ploughing regardless of the condition of the land being ploughed.

The object of the invention is to provide a sliding shoe or a wheel shoe making contact with the ground when the plough shares are at set ploughing depth. This sliding shoe or wheel is operatively connected to the land wheel of the plough for the purpose of raising or lowering the land wheel so as to maintain the plough shares at their set ploughing depths.

Another object of the invention is to provide a device of the class described which will not interfere with the usual manually operated means of raising the plough share as is necessary when turning the plough or at any time when the plough share must be raised.

A further object of the invention is to provide a device of the class described eliminating the usual manual means of raising or lowering the plough share when ploughing which is at all times dangerous to the operator especially in tractor driven ploughs.

Fig. 1 is a perspective view of a plough equipped with our improved device.

Fig. 2 is an enlarged side elevational view of our improved plough governor, per se.

Fig. 3 is a top plan view thereof.

Fig. 4 is a detail perspective view of the hand lever release mechanism as embodied in our improved device.

Fig. 5 is a perspective view of one of the hand lever stop rings as embodied in our improved device.

Fig. 6 is a fragmentary view of a portion of Fig. 2, but illustrating a modified form of the device.

In Fig. 1 of the accompanying drawing we have shown a plough of the usual conventional design and construction such as ordinarily employed for ploughing land prior to planting, cultivating or the like. This plough comprises the usual frame work, 10, rear wheel 11 and furrow wheel 12. The usual land wheel 13 is rotatively mounted on the bottom free end of an arm 14 ex-

tending from a land axle 14' pivotally attached to the frame work 10. The land axle 14' is operatively connected by means of an arm 15^a and a tie rod 15 to the usual hand lever 16, as a means of manually raising or lowering the land wheel 13 by turning the land axle 14'.

This hand lever 16 is of the usual well known type and is provided with a hand element 17 and conveniently located latch 18 operatively connected to the plunger 19 adapted to removably engage in notches 20 formed in the segment bar 21 as a means of holding the land wheel in any desired raised or lowered position.

The only time that plunger 19 on lever 16 may be engaged in the teeth or notches 20 in the segment rack or bar 21, is when the plow is being raised out of the ground for long road transportation and the raising of shares 22, 23 and 24 is desired. In which case lever 16 may be pulled down by the operator's hand against the stop ring 55, and U lock 52 moved off the latch 18, to release plunger 19 and engage it in the notches 20, in the segment 21.

It is to be understood that in the field, either ploughing or turning corners, plunger 19 on lever 16 has to be pulled up away from notches 20 and constantly locked in disengaged position by U lock 52, in order to allow lever 16 free back and forth movement over the segment rack 21 by following the plough governor's actions or operations according to change of soil, without operator's attention.

The usual plough shares 22, 23 and 24 are mounted in the usual well known manner on the lower extended extremities of the plough share beams 25, 26 and 27 respectively pivotally attached to the frame work 10. These plough share beams are operatively connected by means of the tie rod 28 to the above mentioned hand lever 16, as a means of manually raising or lowering of the plough shares.

It is understood that the above described construction is that of the usual standard plough, as above set forth, and that we do not necessarily limit the use of our invention to ploughs of the above described construction,

but to all classes and types of ploughs. It is further understood that structural changes may be made in our device as may be required to adapt same to the various types of ploughs without departing from the invention.

As here embodied our improved ploughs governor comprises a shaft 30 rotatably mounted in a support 31 or tubular member secured as at 32 and 33 preferably by conventional U bolts to the frame work 10 in proximity to the above mentioned plough shares 22, 23 and 24. An arm 34 is secured as at 35 to the clamping member 36 and is extended downwardly therefrom and has secured thereto at its extended extremity a shoe 37 somewhat curved or convex. This clamping member 36 has formed therein an opening 38 adapted to receive the shaft 30 and is removably secured thereto by a bolt 39. An elongated slot 40 is formed in the clamping member 36, communicating with the opening 38 so as to permit the bolt 39 to securely attach the clamping member 36 to the shaft 30. The above described construction is such as will permit the shoe 37 to contact with the ground when the plough shares are at their set ploughing depth. It is understood that the shoe 37 will slide along the surface of the ground when ploughing.

The shaft 30 is provided with an upturned portion 41 having formed therein a plurality of apertures 42 adapted to receive a pin 43. A pair of cross supports 45 and 44 are secured at one extremity to the upturned portion 41 of the shaft 30 by means of a pin 43. These cross supports 44 and 45 are secured at their extended extremities by a pin 46 to the extended extremity of a lever 47. The lever 47 is rigidly secured as at 48 to the extended portion or lug element 49 of the above mentioned land axle 14'. The cross supports 44 and 45, and the lever 47 have formed therein a plurality of apertures 50 and 51 respectively adapted to receive the pins 43 and 46 as a means of adjustably attaching the cross supports 44 and 45 to the upturned portion 41 of the shaft 30 and to the lever 47 as a means of securing desired relation of the shoe 37 to the land wheel 13.

The above described construction is such as will permit the shoe 37 to raise or lower the land wheel 13 for the purpose of maintaining the plough shares 22, 23 and 24 at a set ploughing depth in the ground. In the event that the ground causes the shoe 37 to move upwards, arm 41 will move forwards and move lever 47 forwards so as to turn axle 14' and move the arm 14 and land wheel 13 downwards. In the event that the shoe 37 moves downwards, the motion would be transmitted to move the land wheels 13 upwards.

In Fig. 4 of the accompanying drawing we have shown a hand lever release mechanism comprising a latch lock 52 of U shape construction having secured thereto at its

extremities a pin 53 adapted to slidably engage in an elongated opening 54 or slot formed in the hand element 17 of the hand lever 16. The above described construction is such as will permit the latch lock 52 to be slidably engaged over the latch 18 as a means of holding the plunger 19 in disengagement with the notches 20 formed in the segment 21 for the purpose of nullifying the action of the hand lever 17, so as to permit of unrestricted action of our improved device.

In Fig. 5 of the accompanying drawing we have shown a hand lever stop ring 55 formed or bent circular or ring shape so as to provide an opening 56, as a means of engaging the stop ring 55 over the segment 21. It is understood that a pair of these stop rings 55 and 57 are provided and that same are securely attached or preferably crimped to the extremities of the segment 21. The latter described construction is such as will limit the movement of the hand lever 16 when our improved device is in operation thereby preventing the hand lever 16 from leaving the segment 21.

In Fig. 6 a modified form of the device has been illustrated in which a shoe wheel 58 is shown rotatively mounted on the end of the arm 34 for functioning similar to and in place of shoe 37. A mud scraper 59 projects from the arm 34 and engages the periphery of the wheel 58 for preventing an accumulation of mud on the wheel.

While we have shown and described the preferred embodiment of our invention, it is to be understood that we do not limit ourselves to the precise construction herein disclosed and the right is reserved to all changes and modifications coming within the scope of the invention as defined in the appended claims.

Having thus described our invention, what we claim as new, and desire to protect by Letters Patent of the United States is as follows:

1. In a device of the class described, a shoe operatively connected to the downwardly extended extremity of an arm, said arm secured to a clamping member, said clamping member secured to a shaft rotatively mounted in a support, said support secured to the frame work of a plough, as a means of permitting the said shoe to contact with the ground when the plough shares of the said plough are at any desired ploughing depth.

2. In combination with a device of the class described, a shoe operatively connected to the downwardly extended extremity of an arm, said arm secured to a clamping member, said clamping member secured to a shaft rotatively mounted in a support, said support secured to the frame work of a plough, as a means of permitting the said shoe to contact with the ground when the plough shares of the said plough are at any desired plough-

ing depth, said shaft provided with an upturned portion, cross supports adjustably secured to the said upturned portion and to a pin carried in the extended extremity of a lever, said lever secured to a lug element of 5 the land axle of the said plough.

3. In a device of the class described, a shoe operatively connected to the downwardly extended extremity of an arm, said arm secured to a clamping member, said clamping 10 member secured to a shaft rotatively mounted in a support, said support secured to the frame work of a plough, as a means of permitting the said shoe to contact with the ground when the plough shares of the said 15 plough are at any desired ploughing depth, said shaft provided with an upturned portion, cross supports adjustably secured to the said upturned portion and to a pin carried in the extended extremity of a lever, said lever 20 secured to a lug element of the land axle of the said plough, as a means of raising and lowering the said land wheel for the purposes of maintaining the said plough shares at any desired ploughing depth.

25 In testimony whereof we have affixed our signatures.

JOHN B. PALUCK.

CASMIR J. PALUCK.
